(57) **CLAIM**

The ornamental design for a biped robot, as shown and described.

DESCRIPTION

FIG. 1 is a first perspective view of a biped robot showing our new design;

FIG. 2 is a second perspective view of the biped robot showing our new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of an encircled portion 9 of FIG. 1;

FIG. 10 is an enlarged view of an encircled portion 10 of FIG. 1;

FIG. 11 is an enlarged view of an encircled portion 11 of FIG. 1;

FIG. 12 is an enlarged view of an encircled portion 12 of FIG. 1;

FIG. 13 is an enlarged view of an encircled portion 13 of FIG. 1;

FIG. 14 is an enlarged view of an encircled portion 14 of FIG. 1;

FIG. 15 is an enlarged view of an encircled portion 15 of FIG. 2;

FIG. 16 is an enlarged view of an encircled portion 16 of FIG. 2;

FIG. 17 is an enlarged view of an encircled portion 17 of FIG. 2;

FIG. 18 is an enlarged view of an encircled portion 18 of FIG. 2;

(Continued)

FIG. 19 is an enlarged view of an encircled portion 19 of FIG. 2; and,

FIG. 20 is an enlarged view of an encircled portion 20 of FIG. 2.

The broken lines in the Figures are for the purpose of illustrating portions of the article that form no part of the claimed design.

The dash-dot-dot broken lines encircling portions of the claimed design that are illustrated in enlargements form no part of the claimed design.
